UNITED STATES PATENT OFFICE.

CHARLES CAREY MANKER, OF OGDEN, UTAH, ASSIGNOR TO GLOBE HEAT, LIGHT AND POWER COMPANY, OF OGDEN, UTAH, A CORPORATION OF UTAH.

CARBURETER.

1,209,463.

Specification of Letters Patent. Patented Dec. 19, 1916.

Application filed January 3, 1916. Serial No. 70,073.

To all whom it may concern:

Be it known that I, CHARLES C. MANKER, a citizen of the United States, residing at Ogden city, Weber county, Utah, have invented a new and useful Improvement in Carbureters, of which the following is a specification.

My invention relates to carbureters and more particularly to a carbureter for carbureting air.

An important object of the present invention is to provide a carbureter which thoroughly carburets the air.

A further object of my invention is to provide a carbureter and means associated therewith whereby the degree of richness of the gas may be varied.

Another important object of this invention is to provide a carbureter having a buoyant mixer associated therewith.

An additional object of my invention is to provide a durable carbureter which consists of few parts and is inexpensive to manufacture and which may be placed on the market at a comparatively low cost.

The above and other objects and advantages of my improvement will fully appear from the following description, taken in connection with the accompanying drawings and be explicitly defined in the appended claims.

On the drawings, Figure 1 is a longitudinal sectional view of a carbureter. Fig. 2 is a top view of the carbureter. Fig. 3 is a longitudinal sectional view of the buoyant mixer, and Fig. 4 is a view of the buoyant mixer taken on the line 4-4 of Fig. 3.

Like characters of reference indicate like parts in all the views.

The numeral 5 denotes the carbureting chamber. Projecting from the top of the carbureter chamber is a tubular guide 6 having a plug 7 threaded into its upper end. Extending from the bottom thereof is a threaded nipple 8. Threaded on this nipple 8 is a T-shaped connection 9. Threaded into one end of this T-shaped connection 9 is a vertical pipe 10 having a valve chamber 11 therein which is provided with valve seats at both ends. A ball valve 12 is arranged within this valve chamber 11. This pipe 10 serves as a means whereby the chamber 5 is filled with hydrocarbon. It will be seen that the chamber 5

may be only filled to a certain level owing to the valve arrangement in the pipe 10, thus obviating the danger of entirely filling this chamber. Threaded into the outer end of the connection 9 is a drain plug 13 whereby any sediment or the like may be drained from the chamber 5.

Mounted within the chamber 5 is a U-shaped pipe 14, one end of which extends above the top of the same, as indicated at 15. The end 16 of this pipe extends within the tubular guide 6. This U-shaped pipe 14 conveys air under pressure from any suitable air compressor to the interior of the chamber 5.

The numeral 17 denotes a buoyant mixer in general. As this mixer is an important part of my invention, it will be set forth in detail. This buoyant mixer embodies a bottom wall 18 and a vertical wall 19. Connecting the bottom 18 and the upper edge 70 of the wall 19 is an inclined wall 20, thus providing an annular float. This inclined wall 20 provides a substantially conical cavity. Extending centrally through the bottom 18 is a relatively large tube 21 having openings 22 adjacent and above the bottom 18. This tube 21 is telescopically engaged on the end 16 of the pipe 14. The upper end of this tube 21 is closed as at 23. Mounted upon this closed end 23 is a vertical stem 24. Carried by the tube 21 are collars 25 and 26.

The numeral 27 denotes longitudinally curved blades having securing tabs 28 thereon which are riveted or otherwise secured to the collars 25 and 26 as at 29. These blades are beveled, as at 30, from their upper outer edges to their lower inner edges so as to fit within the conical cavity. These blades are relatively wide at their inner ends.

Between the collar 26 and the lower end of the wall 20 and around the openings 22 is a chamber 31 where the air and hydrocarbon meet. Mounted upon the tube 21 is a deflecting plate 32 which causes the mixture to flow outwardly between the blades.

Mounted upon the stem 24 are weights 33 which are for the purpose of regulating the richness of the mixture. It will be seen that by adding more weights the buoyant mixer will be moved deeper in the hydrocarbon whereby a rich mixture is produced,

and that by detracting the weights the mixer moves toward the top of the hydrocarbon whereby a less rich mixture is produced.

5 An outlet pipe 34 is mounted in the upper end of the chamber 5 which is adapted to be connected with the service pipe or with any suitable connection to convey the mixture to any container.

10 In the operation of this apparatus the chamber 5 is filled with hydrocarbon which flows in the open end of the pipe 21 and out through the openings 22 and into the chamber 31. Compressed air is now forced through the pipe 14 which strikes the closed 15 end 23 of the member 21 and is deflected downwardly, thence it escapes through the openings 22 and into the chamber 31 which contains some of the hydrocarbon. This compressed air agitates the hydrocarbon 20 which is contained in the chamber 31 and thereby thoroughly vaporizes the same. As this carbureted air flows into the chamber 31 it forces the hydrocarbon that is contained therein against the blades 27 and as the air 25 issues between the blades it thoroughly vaporizes the hydrocarbon that has adhered to the same and at the same time rotates the mixer 17.

30 From the foregoing description taken in connection with the accompanying drawings the advantages of the construction and method of operation will be readily understood by those skilled in the art to which the invention appertains, and while I have 35 described the principle of operation, together with the form of the invention which I now consider to be the best embodiment thereof, I desire to have it understood that the form shown is merely illustrative and 40 that such changes may be made when desired as fall within the scope of the appended claims.

What is claimed is:

1. The combination with a liquid fuel con-

45 taining chamber, of a U-shaped pipe mounted within the chamber for conducting air thereinto, a tube telescopically engaged with the inner end of the U-shaped pipe and having its upper end closed, a buoyant member fixed to the tube and having a cavity in its upper face thereof, the bottom of said cavity constituting a liquid fuel containing chamber, and a plurality 50 of blades fixed to the tube and positioned within the cavity.

55 2. The combination with a liquid fuel containing chamber, of a U-shaped pipe mounted within the chamber for conducting air within the same, a vertically movable tube telescopically engaged with the inner end of the U-shaped pipe and having its upper end closed and its lower end perforated, a buoyant member secured to the lower end of the tube, the upper face of the buoyant member being provided with a relatively 60 large cavity, the bottom of the cavity constituting a liquid fuel holding chamber, and a plurality of blades fixed to the tube and positioned within the cavity.

65 3. The combination with a liquid fuel containing chamber, of an air conducting pipe mounted therein, a tube telescopically engaged with the pipe having perforations at its lower end, and its upper end closed, an 70 annular buoyant member secured to the tube 75 adjacent the perforations and having a relatively large conical cavity in its upper face, the bottom of the cavity constituting a liquid fuel containing chamber, and a plurality 80 of curved blades extending radially from the tube adapted to rotate said tube and buoyant member upon the injection of air in the air conducting pipe.

CHARLES CAREY MANKER.
